US00D612830S

(12) **United States Design Patent**
Kim et al.

(10) **Patent No.:** US D612,830 S
(45) **Date of Patent:** ** Mar. 30, 2010

(54) **MOBILE PHONE**

(75) Inventors: **Kang-Moon Kim**, Seoul (KR);
Young-Ju Yeo, Seoul (KR);
Chang-Hwan Hwang, Goyang-Si (KR)

(73) Assignee: **Samsung Electronics Co., Ltd.**,
Suwon-Si (KR)

(**) Term: **14 Years**

(21) Appl. No.: **29/336,162**

(22) Filed: **Apr. 29, 2009**

(30) **Foreign Application Priority Data**

Feb. 18, 2009 (KR) 30-2009-0006731

(51) **LOC (9) Cl.** 14-03

(52) **U.S. Cl.** ..... D14/138 G

(58) **Field of Classification Search** ..... D14/138 R,
D14/138 AD, 138 AC, 138 C, 138 G, 191,
D14/203.1–203.8, 496, 138 AA, 138 AB,
D14/247–248, 137, 147, 218, 341–347; D10/65,
D10/78, 104; D13/168; D18/7; 455/566,
455/575.1, 575.3

See application file for complete search history.
